APPLICATOR FOR HAIR TREATMENT

Dora L. Adams, Balboa, C. Z.

Application August 9, 1950, Serial No. 11,692

Term of patent 14 years

(Cl. D86—10)

To all whom it may concern:

Be it known that I, Dora L. Adams, a citizen of the United States, residing at Balboa, Canal Zone, have invented a new, original, and ornamental Design for an Applicator for Hair Treatment, of which the following is a specification, reference being had to the accompanying drawing, forming part thereof.

Fig. 1 is a side elevational view of an applicator for hair treatment, showing my new design;

Fig. 2 is a bottom plan view thereof;

Fig. 3 is an end elevational view thereof; and

Fig. 4 is a cross-sectional view thereof taken on the line 4—4 of Fig. 1 and looking in the direction indicated by arrows.

The essential features of my design are shown in full lines.

I claim:

The ornamental design for an applicator for hair treatment, as shown and described.

DORA L. ADAMS.
